UNITED STATES PATENT OFFICE.

JOHN A. ANDREWS, OF CHICAGO, ILLINOIS.

DESIGN FOR A GAME CHART.

Application filed April 16, 1925. Serial No. 13,143. Term of patent 3½ years.

To all whom it may concern:

Be it known that I, JOHN A. ANDREWS, a citizen of the United States, residing in Chicago, Cook County, Illinois, have invented a new, original, and ornamental Design for Game Chart, of which the following is a specification, reference being had to the accompanying drawing, forming part thereof, in which Fig. 1 is a top plan view, and Fig. 2 is an edge view, of the design.

I claim:

The ornamental design for a game chart, as shown.

JOHN A. ANDREWS.
